DESIGN FOR A TIRE CHAIN APPLYING DEVICE OR SIMILAR ARTICLE

Walter H. Kaltreider, York, Pa.

Application December 8, 1941, Serial No. 104,540

Term of patent 3½ years

To all whom it may concern:

Be it known that I, Walter H. Kaltreider, a citizen of the United States of America, residing at York, in the county of York and State of Pennsylvania, have invented a new, original, and ornamental Design for a Tire Chain Applying Device or Similar Article, of which the following is a specification, reference being had to the accompanying drawing, forming part thereof, wherein

Fig. 1 is a perspective view of the tire chain applying device or similar article, showing my new design;

Fig. 2 is a view looking at one side thereof;

Fig. 3 is a view looking at the other side thereof;
and

Fig. 4 is a plan view thereof.

I claim:

The ornamental design for a tire chain applying device or similar article, as shown.

WALTER H. KALTREIDER.
